(57) **CLAIM**

The ornamental design for LED controller, as shown.

DESCRIPTION

FIG. 1 is a perspective view of LED controller showing my new design;

FIG. 2 is an exploded perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view.

The broken lines in FIG. 2 depict an unclaimed part.
